CONDENSER MICROPHONE

Rolf Horkheimer, Berlin, Germany, assignor, by
mesne assignments, to Radio Corporation of
America, New York, N. Y., a corporation of
Delaware

Application November 7, 1936, Serial No. 109,624
In Germany November 21, 1935

5 Claims. (Cl. 179—111)

This invention relates to improvements in or relating to electrostatic microphones of satisfactory efficiency.

It is well known to use very thin and light diaphragms for the manufacture of electrostatic microphones of satisfactory efficiency. Generally, such diaphragms are annularly glued at their circumference in more or less stressed position or maintained in positioned and previously stressed by means of particular devices. The air-cushion situated behind the diaphragm serves substantially as the force of reaction. Thus, a high starting pressure is obtained due to the substantial increase in capacity of the microphone.

The capacity may be increased by reduction of the spacing between the diaphragm and the counter electrode but this reduction is limited by the capability of resisting puncture. The same purpose is obtained by increasing the electrode surfaces. It is also well known to centrally support the diaphragm in order to avoid any contact with the counter electrode due to the great mobility of the diaphragm.

5. In order to comply with the above requirements, diaphragms are made in the known manner from non-conducting material and coated with a conducting surface of like magnitude as the counter electrode. An insulating leading-through device is passed through the axis of rotation of the microphonic body as far as the conducting diaphragm, the latter is then secured to it and the supply conductor is mounted. This entails the following difficulties:

25. The gluing of diaphragms requires utmost care since the agglutinant used runs away most readily over the insulating border zone and may bring about not only impairment of the insulation but even direct short-circuit of the electrodes. The comparatively wide insulating border zone surrounding the conducting part of the diaphragm necessary for this reason leads a fortiori to a reduction of the active electrode surface and thus to a reduction of the starting pressure received from the microphone.

The gluing of the diaphragm presents the disadvantage of the microphone being unserviceable when in spite of all the precautions taken prior to gluing, minute dust-particles have nevertheless adhered to the counter electrode etc. and as a result subsequent removal is impossible without destroying the diaphragm.

Cracking of diaphragms involves circuitous re-

the observance of all conditions involved by manufacture for the first time.

The necessity of supplying the current of the conducting layer to the diaphragm surface in the center thereof involves a difficult fine mechanical work and thus an increase in manufacturing expenses.

These disadvantages are obviated by the present invention. According to the invention, for this purpose the diaphragm is not provided at the point of bearing on the microphonic body, consequently preferably at the border with an insulating border zone. Indeed, it is so constructed that the diaphragm at or adjacent the point, preferably the center, at which is supported from the counter-electrode, is non-conductive or is rendered non-conductive. The diaphragm may therefore be secured directly to the counter-electrode which for this purpose has left on it a small projection.

Current is supplied to the diaphragm according to the invention in the most simple manner by the latter having its conducting layer side mounted directly on the metal casing or body of the microphone. It may be glued thereto directly but according to a further feature of the invention for the sake of its pressure it is preferably glued over a suitably shaped metal ring and is then only laid on the microphonic body. This ensures the possibility of readily interchanging so that mounting difficulties are also overcome and dust-particles can always be removed readily and without expenses.

The small non-conducting surface at the point of support may be made, for example, by removal of the non-conducting coating prior to the mounting on the insulating diaphragm layer. When the metal layer is formed by cathode disintegration or like procedures, a small circular mica-disc may be laid on the point concerned so that this point is kept free from the metal layer. The procedure followed may, however, be such that the diaphragm rendered conducting per se throughout its surface is rendered non-conducting at the point of support by painting with an insulating lacquer or the like. This procedure may be followed, for example, with diaphragms that are only made of metal.

In order that the invention may be clearly understood and readily carried into effect, one embodiment thereof will now be described more fully hereinafter with reference to the accompanying drawing, in which:

Fig. 1 shows a condenser microphone of the construction used hitherto, whereas

Fig. 2 shows a form of construction of the microphone according to the present invention.

Referring to Fig. 1, 11 designates the microphonic body which has arranged in it the stationary condenser electrode 13. It has centrally arranged in it the leading-through device 14 and insulated therefrom the supply conductor 15 for the movable electrode. In this case, the movable electrode is constituted by a collodion film 16 glued to the outer edges of the microphonic body 11 after prior stressing and having on its lower side a metallic coating 17 which, however, only covers the inner part of the diaphragm and the circumference of which is separated from the microphonic body 11 by an insulating border zone 18. The accurate fitting of the insulating leading-through device 14 and the arrangement of the supply conductor 15 involved extremely great precision and nevertheless by reason of the microphone being made up from any parts, it did not warrant correct adjustment for long intervals of time.

These difficulties are overcome by the form of construction according to the invention shown in Fig. 2 in which, as before, the stationary or central electrode 23 is arranged supported in position by an insulating intermediate layer 22, located in the microphonic body 21. Instead of the insulating leading-through device, this electrode has only in the center a small trunnion 24 having a height equal to the distance from the diaphragm and being made with advantage in one piece with the electrode 23. The diaphragm 26 of collodion or other suitable insulation material is provided with the metal coating 27 except, for a part in its center and glued to a metal ring 25 after prior stressing. This ring 25 permits of the diaphragm being readily mounted securely but readily removably on the condenser body 21 which for this purpose is provided with a ledge 29. The metal coating 27 of the diaphragm is separated by the border zone 28 insulating the diaphragm from the trunnion 24 of the stationary electrode. When comparing the two forms of construction for equal diameters of diaphragm it is obvious that the space occupied by the border zone 28, if premised that the widths of the border zone are equal, is smaller than the space occupied by the border zone in the embodiment hitherto used shown in Fig. 1.

What is claimed is:

1. An electrostatic microphone comprising an outer metallic casing having a ledge surrounding the outside surface, an insulating member within said casing, a central electrode within said insu-

lating member, a projection on said central electrode, a ring seated on said ledge, a diaphragm secured and electrically connected to said ring, said diaphragm forming a movable electrode and having insulating means for resting on the projection of said central electrode.

2. An electrostatic microphone comprising an outer metallic casing having a ledge surrounding a portion of the outside surface, an insulating member within said casing, a fixed electrode mounted on said insulating member, a projection on said fixed electrode, a metallic annular member seated on said ledge, a diaphragm secured and electrically connected to said annular member which rests on the ledge of said casing, said diaphragm forming a movable electrode and having insulating means for resting on the projection of said fixed electrode.

3. An electrostatic microphone comprising an outer metallic casing having anchoring means on a portion of the outside wall thereof, an insulating member concentric with the inside wall of said casing, a fixed electrode concentrically located within said insulating member, a small central projection on said fixed electrode, a diaphragm secured beyond the outer periphery of said casing by said anchoring means and electrically connected thereto, said diaphragm forming a movable electrode and having insulating means for resting on the projection of said fixed electrode.

4. An electrostatic microphone comprising an outer metallic casing, an insulating member resting on at least one wall of said casing, a fixed electrode within said insulating member, a central projection on said fixed electrode, a metallic diaphragm having an aperture therein, said aperture being covered by an insulating layer which rests on said projection, said metallic diaphragm being electrically connected to the outer periphery of said casing.

5. An electrostatic microphone comprising an outer metallic casing having anchoring means on a portion of the outside wall thereof, an insulating member resting on at least one wall of said casing, a fixed electrode within said insulating member, a small projection on said fixed electrode, a metallic diaphragm having an aperture therein, said aperture being covered by a film of non-conducting material which rests on said projection, said metallic diaphragm being secured by said anchoring means and electrically connected to the outer periphery of said casing.
